UNITED STATES PATENT OFFICE.

GUIDO TALLEI, OF ROME, ITALY.

AIRSHIP WITH MIXED SUSTENTATION.

Application filed September 29, 1926, Serial No. 138,464, and in Italy October 13, 1925.

The present invention concerns a novel type of airship with mixed sustentation, that is an airship provided with supporting surfaces in such a manner as to obtain as a result a flying machine which while possessing all the advantages of the usual airplanes and airships assembled together eliminates as far as possible the inconveniences of both types.

10 The airship according to the present invention consists substantially of a central hollow body of elongated shape on the lateral walls of which are externally secured carrying surfaces symmetrically disposed in respect of the middle longitudinal plan of the apparatus.

The central body consists of a gas bag of aluminium sheet or of any other light metal sheet; said envelope is carried by a supporting and stiffening frame and contains in its interior air heated by means of the exhaust gases of the engines, so as to produce a statical lifting power to which, during the flight is added the dynamical lifting power due to the pressure which the external air develops against the lateral carrying surfaces, which act in the same manner as the wings of an usual airplane.

In the annexed drawing, which shows by way of example and schematically a practical embodiment of the invention:

The Fig. 1 is a top view of the airship partially in section,

The Fig. 2 is a cross section according to the line A—B of Fig. 1,

The Fig. 3 is a side view and

Fig. 4 is an axial horizontal section.

As shown in the drawing the airship according to the invention substantially consists of an envelope 1 of thin corrugated metal sheet covered by an outer skin which is of thin smooth metal sheet. Said double envelope which constitutes a strongly insulating wall has, in the usual way, the shape of a surface of revolution the longitudinal axis of which is much longer than the transverse axis. At the fore end is provided a strong bow shield 2 designed to resist the dynamical pressure of the external air when the airship is in motion, and at the rear end, that is at the stern, are provided the rudder 3 and the stabilizing surfaces 4 which can be controlled from the cars by means of a

rigid or flexible transmission of any convenient type. The cars 5 are symmetrically placed at both sides of the envelope.

In order to impart to the latter the necessary resistance it is mounted upon ring shaped frames 6 conveniently distanced and connected by means of stiffening and supporting spokes 7 to a central tube 8 extending for the whole longitudinal axis of the airship. This tube is closed at the fore end and freely open at the rear end for the purpose which will be explained hereinafter.

In fact said tube has not only the purpose of acting as a hub for the attachment of the spokes 7 but is also intended to receive in proximity of its fore end, the exhaust gases which through the radial tubes 20 come from the engines 19 placed in the cars 5. The exhaust gases thus flow through the central tube 8 and heat strongly the air contained between the internal walls of the envelope 1 and the external wall of the tube 8.

The increase of temperature thus obtained causes a rarefaction of the air contained in the envelope and therefore the production of a certain amount of lifting power which contributes in lifting the airship.

In the walls of the central tube 8 openings 21 may be provided through which the exhaust gases may escape in the interior of the envelope. In this manner the lifting power can be notably increased because a higher temperature can be maintained in the interior of the envelope.

To the lifting power thus obtained is added the dynamical lifting power supplied by two or more sets of wings 9 and 10 applied to the sides of the envelope. Said wings are rigidly fastened to the framing of the envelope 1, and possess further the feature of carrying at the rear fan shaped appendages 11 and 12 which can be displayed or applied at will by means of convenient controlling transmissions for the purpose of changing the area of the carrying surface according to the circumstances. The stabilizing surfaces have been also, and for a like purpose, provided with fan shaped extensions 13 and 14.

The airship according to the invention being particularly designed for very long travels with many passengers, thus instead of adopting a large number of separate cars

it has been found preferable to arrange two great cars, the common bottom 17 of which forms also a supplementary wing, inter-communicating through a passage 15 pro-
5 vided in the body of the envelope, and for this purpose the envelope shows a recess 16 corresponding to the fore end of said cars.

The propulsive power is supplied by two sets of engines 19 symmetrically placed in
10 respect of the central body on board of the two cars, the hulls of which are conveniently shaped, in such manner as to allow the application of several propellers 18 to each one of them.

15 Further a not negligible increase of the propelling power is due to the arrangement above mentioned that the exhaust gases escape in the axial direction at the rear end of the longitudinal conduit 8, the reaction of
20 the jet supplying a useful component for the forward movement in the same way as it happens in a jet propelled ship.

In the form of construction of the airship shown in the drawing an attempt has
25 been made to give the airship an external shape as similar as possible to the shape of a flying bird, the structure showing parts which correspond to the beak; the head, the neck, the wings and the tail, although it
30 will be understood that said shape can be considerably changed always remaining within the scope of the invention.

The airship built and working in the manner above said possesses considerable advantages in comparison of the other airships
35 of the same class already known.

In the first place any danger of fire due to the presence of hydrogen is completely eliminated, the combustible gas being replaced
40 by hot air, which produces also a great economy in the cost.

In the second place the long and wide conduit through which the exhaust gases are discharged allows a very silent running
45 of the engines which is an important feature when the airship is intended for war service.

In the third place it does not require the usual costly and complicated plants for renewing the gas supply and for landing and starting, as this airship can land and start like an airplane and float like a ship and may be anchored in any harbour.

It will be further understood that the airship will be supplied with self-acting or controlled valves for keeping within the

prescribed limits the pressure in the interior of the envelope; with ventilators for accelerating or retarding the change of the air and of the exhaust gases and for keeping
50 them in the desired proportion in the interior of the envelope; may be provided with vertical pits giving access on the deck of the envelope and finally with all the other structures and contrivances required for the
55 regular working of an airship, and which do not need to be here described or mentioned more in detail, being all generally known.

I claim:

1: An airship with mixed sustentation, comprising an engine, supporting surfaces to supply in flight aerodynamical lifting power; an envelope of sheet metal and filled with air, a hollow tube extending along the longitudinal axis of the envelope, the exhaust gases of the engine being led to said longitudinal tube for the purpose of heating the air contained in the envelope and thus supplying aerostatic lifting power, ring shaped girders supporting the envelope, and spokes radiating from said hollow longitudinal tube for stiffening the girders.

2. An airship according to claim 1 wherein in the longitudinal tube is provided with openings in its wall so that the exhaust gases can pass into the interior of the envelope and become mixed with the air contained therein.

3. An airship according to claim 1 wherein the envelope is formed of corrugated sheet metal and an external covering of smooth sheet metal so as to secure a good thermal insulation of the hot air in the envelope.

4. An air ship according to claim 1 the shape of which is like the shape of a flying bird, having parts corresponding to the beak, the head, the neck, the body, the wings and the tail, cars at both sides of the body, the neck being formed with a recess to enable communication between the cars.

5. An air ship according to claim 1 together with cars mounted adjacent the envelope, said cars being inter-communicating and so shaped as to permit the use of a plurality of propellers for each car.

In testimony whereof I have affixed my signature at Rome this fifteenth day of September, 1926.

GUIDO TALLEI.
